UNITED STATES PATENT OFFICE.

NEHEMIAH T. FOLSOM, OF BOSTON, MASSACHUSETTS, ASSIGNOR TO JOHN S. FOLSOM, OF SAME PLACE.

DUST-PAN.

SPECIFICATION forming part of Letters Patent No. 276,531, dated April 24, 1883.

Application filed December 6, 1882. (No model.)

To all whom it may concern:

Be it known that I, NEHEMIAH T. FOLSOM, of Boston, in the county of Suffolk and State of Massachusetts, have invented certain Improvements in Dust-Pans, of which the following is a specification.

This invention has for its object to prevent the forward edge of a dust-pan from being bent and distorted; and to this end it consists in shoeing or re-enforcing the said edge with a strip of steel or equivalent metal having sufficient elasticity to prevent it from being indented and bent.

Of the accompanying drawings, forming a part of this specification, Figure 1 represents a top view of a dust-pan embodying my improvement. Fig. 2 represents a section on line *x x*, Fig. 1.

The same letters of reference indicate the same parts in all the figures.

In carrying out my invention I secure to the front edge of a dust-pan, *p*, a strip, *s*, of steel, brass, manganese, bronze, or other material having such a degree of elasticity that it will not readily become indented and will conform readily to the floor or other surface from which dust or dirt is to be swept into the pan. The strip or shoe *s* may be of any desired form and thickness and may be secured to the pan by any desired means, as by soldering or riveting. The shoe may be made so thin as to be flexible or yielding or may be rigid and inflexible. I have found that a shoe of the character described attached to an ordinary sheet-iron dust-pan preserves the edge in shape, and enables the edge to fit closely on a floor or other flat surface.

It is well known that an ordinary dust-pan, having its forward edge of the same material as the body of the pan—viz., sheet-iron—will soon become indented and incapable of fitting closely against a flat surface. Doubling the thickness of the edge by bending it over upon itself or adding thereto a strip of the same material simply increases the stiffness of the edge without preventing it from being indented.

I am aware that dust-pans have been stiffened by strengthening plates or ribs of soft metal; but this, while it adds strength, does not prevent the indenting of the edge, so prejudicial to this class of articles. By combining a blade of stiff elastic metal with the edge of the pan, to form practically a continuation of the body, the latter will spring so as to fit close to the surface from which the dust is to be taken, and will not bend or buckle like iron, but will retain the form and preserve that of the pan.

I claim—

A dust-pan the forward edge of which consists of a blade of stiff elastic metal secured to and forming a continuation of the body of the pan, as set forth.

In testimony whereof I have signed my name to this specification, in the presence of two subscribing witnesses, this 25th day of November, 1882.

NEHEMIAH T. FOLSOM.
